UNITED STATES PATENT OFFICE.

RYALL H. CARTMELL, OF DETROIT, MICHIGAN.

START AND STOP SIGNAL FOR RAILROAD-CARS.

1,120,025.

Specification of Letters Patent.

Patented Dec. 8, 1914.

Application filed February 9, 1914. Serial No. 817,479.

To all whom it may concern:

Be it known that I, RYALL H. CARTMELL, a citizen of the United States, residing at Detroit, in the county of Wayne and State 5 of Michigan, have invented certain new and useful Improvements in Start and Stop Signals for Railroad-Cars, of which the following is a specification.

This invention relates to starting and 10 stopping signals for railroad trains, and especially to electrically-operated trains, each individual car of which has its own conductor, while the motorman is located in the vestibule of the front car.

15 The invention has for one of its objects the provision of an improved signal system whereby the motorman may receive signals as to starting and stopping, at different points along the road.

20 The invention has, furthermore, for its object the provision of a system which comprises a signal adapted to be set into the "starting" position as soon as every conductor on the train has signified his wish to proceed, it being understood that the omission 25 of a single conductor's signal will not set the indicator to its "starting" position.

The invention has, also, for its object the 30 provision of a signal system including an indicator which can be set into and maintained in the "starting" position, as long as said circuit is closed, while any interruption or break in said circuit, no matter from what cause, will allow said indicator to re-

35 turn to "stop".

A further object of the invention resides 40 in the provision of means whereby each conductor is enabled to verify, for himself, which particular position his own individual circuit-closing device is in, without referring to the device operable by any of the other conductors.

45 Further objects of the invention will hereinafter appear and be particularly defined in the claims.

The invention has been clearly illustrated 50 in the accompanying drawings in which similar characters denote similar parts and in which—

55 Figure 1 is a diagrammatic view of a pair of connected railroad cars equipped with my improved signal system. Fig. 2 is a face view of the circuit breaker such as is located in each car and operable by the conductor of such car. Fig. 3 is a side view thereof, and Fig. 4 is a view similar to Fig. 2, but

illustrates the controlling member of the breaker in another position.

Briefly stated, the present system comprises a signal or indicator for the motorman which is so organized with the sections of the operating circuit that, when the starting signal is to be given, the conductor of each car will pull a cord to set the circuit breaker for his car so as to complete the circuit at that point. When he has done so, he will be informed of this fact, preferably by one or more tell-tale lights which will remain burning as long as his circuit breaker remains in that condition. In a like manner the conductor of any other car will have to pull his cord to produce the same effect. From this it will be understood that each car, or more properly speaking each individual conductor, will simply complete the circuit by his own breaker without influencing any of the others, so that consequently it is necessary that all the circuit breakers are closed in order to transmit the starting signal to the motorman. When now a stop signal is to be given, the present organization is such that another pull given by any conductor to his cord, will again break the circuit at that point, therefore allowing the motorman's signal to resume its "stop" position. The same effect will be produced by the break of any connection between the cars themselves or in any of the wires passing through the train or, by perchance, if the trolley should leave its wire.

90 Referring now to the drawings, A denotes in outline, the first or head car of a train which comprises also a coach B, but may contain more, if so desired, all of the coaches behind the head coach being considered as trailers, while as a matter of fact under the present system it is desirable that the power connection be established between the trolley wire T and the car A through a trolley pole P and the bus wire 95 W which extends to the front of the first car as usual. Connections between the bus wire sections as pertaining to the different cars are also made in the usual manner, as for instance by jumpers J. The electric 100 current carried by the bus wire W is used for transmitting the signals above described, it being understood that transformers, resistance boxes and the like may be used as required under different conditions 105 of service.

Leading from the bus wire W in car B, is

a branch wire w which leads to one member of a pair of terminals 10, 11, both of which are secured to an insulating block 12 carried by a bracket 13 which may be secured in fixed position at any suitable point within the car, preferably at one end thereof, so that the device whereby the make and break of the circuit is established, can be operated by a cord from any point longitudinally of such car. The other member 11 of the above mentioned terminals, is connected with a feed wire 14 leading to a series of lamps 15 which are wired in parallel through an electric conductor 16 grounded on the truck of the car, so that when the terminals 10 and 11 are connected, the lamps will be lighted. This electric connection is established by any one of a series of metallic plates 17 set into the periphery of a roller 18 made of insulating material and journaled on a stud 19 which is rigidly held in the bracket 13 above mentioned. This roller 18 is in the present instance provided with four of these metallic plates 17, and the mechanism for rotating the roller is intermittent by virtue of the employment of an oscillatory lever 20 which carries a pawl 21 adapted to engage successively the teeth of a ratchet wheel 22 secured to said roller. In the present instance the swinging movement of the lever 20 is limited to 45 degrees, and it will therefore be understood that when the lever 20 is moved from the position shown in Fig. 2 to that shown in Fig. 3, the terminals 10 and 11 will, in the latter position of the roller 18, be disconnected, and the lamps 15 will therefore be extinguished. The particular purpose of these lamps is that of indicating to the conductor by visible means what the actual condition of the breaker roller 18 is in, as far as the making or breaking of the indicator-controlling circuit for the motorman's signal is concerned. The latter circuit comprises a branch wire w' which leads to a terminal or brush 23 adapted to be electrically connected with a brush 24 when the roller 18 is in the position shown in Fig. 2, both terminals 23 and 24 being also secured to the insulating block 12 in such a manner that no electric connection will exist between the several contact members carried by the same. The terminal 24 is connected with a solenoid 39 to be hereinafter referred to, and thence to a wire 25 which is connected by a jumper 26 with a feed wire 27 of the next adjacent or head car A. This feed wire 27 leads to the terminal 23 of the circuit breaking device in the head car, and its companion terminal 24 is connected through a wire 28 with one pole of an electromagnet 29, the other pole of which is grounded through a wire 30 as shown. It will therefore be evident that when the breaker device in car A is in a position like

that of car B, an electric connection will be established to energize said electromagnet 29 which therefore will attract an armature lever 31 shown herein as a gong hammer which is retracted away from the gong 70 when the electromagnet 29 is energized, but will be permitted to drop to strike said gong whenever the circuit is, for any reason, interrupted. In the position illustrated in Fig. 1, the breaker is in its "disconnected" 75 position, and the magnet 29 is therefore non-operating. When, now, the conductor of car A pulls the cord C, the breaker will be moved from the position shown into one corresponding to that of car B, in which case the electromagnet 29 will then become active in moving the armature 30 into the "go" position. While this movement will naturally produce a click, means may be provided whereby the "go" signal is visibly 80 given, as for instance by a light 32 which however may be switched out, when desired, by the hand-switch 33, especially during the day time.

The operating lever 20 of the breaker device is movable between a pair of stops 24 and 35 secured to or forming a part of the general plate 36 of the breaker device, the cord C constituting the hand-pulled member operated by the car conductor, while a 95 spring 37 serves to return the lever 20 to its normal position shown in Fig. 2.

From the foregoing it will be understood that in order to transmit the "go ahead" signal to the motorman, the breakers in all 100 the cars of the train will have to be in their circuit-closing position, but any one of the several car conductors, or in fact any passenger on the car, may give a stop signal without having to consider any other car of the 105 train, inasmuch as the stop signal is given at once by the interruption of the starting circuit. It will also be understood that, under the system thus far described, one break in the circuit is all that is necessary to give 110 the "stop" signal, and that when the same break is re-made, the "start" signal will be immediately given, without considering the breaker in any other car. Under some 115 circumstances, such condition may be detrimental to the safe operation of the train, because, after the train has come to a stop on the signal given by one conductor, passengers may enter or leave the cars controlled by other conductors (who may not 120 have pulled their cords to give the "stop" signal) even after the first-named conductor is ready to proceed and pulls his rope accordingly to re-make the circuit in his car. In order to avoid this objection, the present 125 invention comprises means whereby the circuit-breaking movement of any one breaker in the train will result in a similar movement of each and every other breaker of the train, automatically. In other words, if 130

breaker of car A is moved to give the stop signal by the interruption of the circuit, the breaker of car B will be similarly set by the return movement of an electrically-operated device, such as the movable core 38 of a solenoid 39 which is in circuit with the signal devices in the motorman's vestibule of the car. As long as the current flows through the circuit and energizes the solenoid 39, the core 38 thereof will remain in position shown in Fig. 2; but as soon as the flow of current is interrupted said core will be shifted into position shown in Fig. 4 by means of a spring 40, this return movement of the core being effected by a spring-actuated pawl 41 operative upon the ratchet 22 above described, to turn the latter for one-eighth of a rotation and quickly throwing the roller 18 into position shown in Fig. 4. The pawl-carrying member of the core is provided with an extension 38' which, when the core is operated by the spring 40, will strike against the stop-pin 34 above described and therefore limit the return movement.

In order to prevent the roller 18 from passing beyond its intended position, a series of notches 42 are provided in its periphery adapted to be engaged by the terminals 30 or brushes 11 and 24 above mentioned.

It will be noted, by referring to Fig. 2, that, when the lever 20 is moved toward the left, the brush 23 will be the first to leave the metallic plate 17, and before the other plate 17 on the opposite side of the roller will have disconnected the terminals 10 and 11 which pertain to the light circuit. Inasmuch as the breaker in the circuit established by the brushes 23 and 24 becomes broken as soon as either of said brushes (23) has left the contact plate 17, and the spring 40 can then immediately act to bring the core to the normal position shown in Fig. 4, it follows that the movement of the roller 18 will then establish a quick break between the brushes 10 and 11 of the light circuit, regardless of the speed with which the lever 20 is moved.

The operation just described in connection with the breaker of car A is just the same in car B, or in fact in any other car of the train. Hence it follows that in order to give the starting signal, the breaker in each car will have to be separately set into its "make" position, before the motorman will receive the "go-ahead" signal. On the other hand, if it should be desired, that the system as first described, be used, without the solenoid effecting any functions, it will be only necessary to throw the pawl 41 into such position that it will not operate upon the ratchet 22 in either direction, this condition of the system being illustrated in Fig. 1.

While in the accompanying drawings, I

have illustrated two cars, it is evident that the number of trailers can be varied as desired without in any way affecting the operation of the system as a whole. Likewise it should be understood that each individual car may be wired with a signal at its front end in just the same manner as the car A is provided with the same. In the present drawings the motorman's signal has been omitted in the trailer, merely for the sake of avoiding confusion. It should also be understood that the trolley P can be connected with the bus line of any one car without affecting the operation of the system, and if desired, a single car, as for instance the one designated by A, may constitute the entire train, in which case all the change necessary to be made is that of electrically connecting the ends of the bus line and the car line 27 preferably at the rear end of the car and through the intervention of a jumper.

Changes may be made in my improved system, especially in the particular construction of the breaking mechanism, without departing from the spirit of the invention.

I claim:—

1. The combination with an indicator, of an electric circuit therefor, a plurality of breakers connected in series in said circuit, means for moving said indicator into one position when all of said breakers are closed, means for moving said indicator into another position when said circuit is open, and secondary circuits controlled by said breakers respectively, each comprising a tell-tale device for indicating the position of each particular breaker.

2. The combination with a plurality of vehicles, of an indicator in one of said vehicles, an electric circuit including said indicator and extending through said vehicles, a circuit breaker in each vehicle and included in said circuit, means for moving said indicator in one direction when all of said breakers are closed, means for moving said indicator into another position when any one of said circuit breakers is open, and a tell-tale circuit for each breaker and operable thereby for indicating the open or closed positions of the same.

3. The combination with a plurality of vehicles, of an indicator in one of said vehicles, an electric circuit including said indicator and extending through said vehicles, a circuit breaker in each vehicle and included in said circuit, means for moving said indicator in one direction when all of said breakers are closed, means for moving said indicator into another position when any one of said circuit breakers is open, and means for setting each circuit breaker into its "break" position by the movement of any other breaker in the circuit.

4. The combination with a plurality of

vehicles, of an indicator in one of said vehicles, an electric circuit including said indicator and extending through said vehicles, a circuit breaker in each vehicle and included in said circuit, means for moving said indicator in one direction when all of said breakers are closed, means for moving said indicator into another position when any one of said circuit breakers is open, and 10 electrically operated devices in said circuit and coöperative with said circuit breakers respectively and operative for setting each circuit breaker into its "break" position by the movement of any other breaker in the circuit.

5. The combination with a plurality of vehicles, of an indicator in one of said vehicles, an electric circuit including said in-

dicator and extending through said vehicles, a circuit breaker in each vehicle and included in said circuit, means for moving 20 said indicator in one direction when all of said breakers are closed, means for moving said indicator into another position when any one of said circuit breakers is open, and 25 solenoids, each comprising a movable core and a pawl carried thereby for setting each circuit breaker into its "break" position by the movement of any other breaker in the circuit.

In testimony whereof I affix my signature in presence of two witnesses.

RYALL H. CARTMELL.
